UNITED STATES PATENT OFFICE.

FRANK S. TWOMBLY, OF MANCHESTER, NEW HAMPSHIRE.

MILK-JAR PROTECTOR.

SPECIFICATION forming part of Letters Patent No. 712,446, dated October 28, 1902.

Application filed June 2, 1902. Serial No. 109,877. (No model.)

To all whom it may concern:

Be it known that I, FRANK S. TWOMBLY, a citizen of the United States, residing in Manchester, in the county of Hillsboro and State of New Hampshire, have invented a certain new and useful Improvement in Milk-Jar Protectors, of which the following is a specification.

This invention relates to milk-jar protectors or locking devices for preventing jars or their contents from being stolen or tampered with when left outside at doors of houses.

It is customary for milkmen to deliver milk to retail customers at the doors of houses and apartments in glass jars in the morning before the customers are awake, and it frequently happens that the jars or their contents, or both, are stolen before they can be taken in by the customer, or are otherwise tampered with.

20. The device herein described and claimed securely clamps the jar and covers the top of the same at the outside of the house or apartment in such a manner as to prevent the removal of the jar or its contents until the door is opened, because to remove the jar from the clamp it is necessary to release or unlock the clamp from the inside of the house or apartment with one hand while the jar is held by the other hand.

30. The device is therefore secured upon the inside and outside of the house or apartment and extends through the lock-jamb of the door, by "lock-jamb" meaning the jamb contiguous to the lock-stile of the closed door, or through the wall adjacent to said jamb.

In the accompanying drawings, on two sheets, Figure 1 is an oblique view of the external portion of the device secured to a building or house and retaining a jar; Fig. 2, 40 a front elevation of the external portion of the protector secured to the side of a building and holding a jar; Fig. 3, a side elevation of the device holding a jar and secured to a door-jamb; Fig. 4, a side elevation of the locking device; Fig. 5, a front elevation of the device detached; Fig. 6, a horizontal section on the line 6 6 in Fig. 2 or Fig. 3, showing the protector unlocked; Fig. 7, similar to Fig. 6, showing the protector holding a jar; Fig. 8, a vertical longitudinal section on the line 8 8 in Fig. 5 of the bracket portion of the device; Fig. 9, a rear elevation of the

protector attached to the jamb, showing the locking device.

A represents the outer wall of a house or building, B a door, and b the lock-jamb of said door, all of any usual construction.

C is a bracket consisting of a wall-plate c, shelf c', and ledge c², preferably metallic and formed of a single casting. The plate c is provided with one or more holes c³, by which it may be secured to the outer surface of the jamb b or to the outer surface of the wall adjacent to the jamb, as by nails or screws c⁴. The shelf c' may be used to support an empty jar; but its principal function is to cover the top of a jar secured in the protector in such a manner as to prevent the removal of the stopper, cap, or cover which may be used to seal said jar in any usual manner, and thereby prevent removing or tampering with the contents of the jar. The horizontal ledge c², which serves as the fixed jaw of the clamp of the protector, is therefore arranged at such a distance below said shelf that when the under side of the head d of the sealed jar rests upon the top of said ledge the top of the head or the seal will touch or come in close proximity to the bottom of said shelf. The front of the ledge is concaved at c⁵ to fit the neck d' of the jar and is provided with a transverse groove c⁶, Figs. 6 and 8, which may serve to receive a name-plate secured on the neck of the bottle. The movable jaw of the clamp consists of a bow or J shaped loop F of stout wire, the arms f, f' of which are passed through holes c⁷ c⁸ in the bracket C, preferably near the ends of the ledge c', and have a limited sliding movement through said holes to allow said loop to clasp the neck d' of a jar D below the head d of said jar firmly against said ledge or to allow said head to be passed up freely into said loop in front of said ledge. The long arm f of the loop reaches through the wall or jamb and through a stop-plate H, as shown in Figs. 3, 4, 6, and 7, the free end portion of said long arm passing through a hollow boss h, cast or otherwise secured on said stop-plate, said stop-plate being fastened to the inner face of the wall or jamb, as by screws f⁹, in an obvious manner. The free end portion of the arm f is screw-threaded at f⁸ to engage a nut f² and check-nut f⁷, and to the nut f² is pivoted at f⁵ between ears f³ f⁴, which project

from said nut f^2 , a latch f^6 , which rests upon the boss h when the loop is open, as in Fig. 6, but falls down upon the arm f between the outer end of said boss and said nut f^2 when 5 said loop is pushed in far enough to clasp a jar, as shown in Fig. 7, and in the last position prevents the loop from being opened. This arrangement of nuts and latch permits the adjustment of the pivot to the proper position, taking into account the various thickness of walls and jambs. It is only necessary to make the arm f long enough and after adjustment of the nut and check-nut to proper position any undesirable projection of said 10 arm beyond the check-nut may be cut off. The latch and nut prevent the short arm f' from being drawn entirely out of the plate c .

In practice the customer at night leaves the loop projecting to its full limit, the latch 20 being raised up and resting upon the boss h and the empty jar resting upon the shelf c' . The milkman places the neck of the full jar in the loop and presses the loop toward the ledge until the latch drops into engagement 25 with the boss h .

I claim as my invention—

1. A jar-protector, consisting of a clamp adapted to be permanently secured on the outer side of a wall or jamb and to grasp the 30 neck of a jar, and means of locking said clamp adapted to be arranged at the inner side of said wall or jamb.

2. A jar-protector, consisting of a clamp, adapted to be secured on the outer side of a wall or jamb and to grasp the neck of a jar 35 and means of locking said clamp, adapted to be arranged at the inner side of said wall or jamb, and a shelf secured at a fixed distance above said clamp to cover a jar held in said 40 clamp and to prevent the removal of the stopper of said jar.

3. The combination of a bracket provided with a fixed ledge and adapted to be secured to the outer side of a wall or jamb, a loop, 45 forming with said ledge a clamp and passing through said bracket and having an arm adapted to pass through said wall or jamb, and locking means, adapted to be arranged at the inner side of said wall or jamb and to

lock said arm, to prevent the opening of said 50 clamp.

4. The combination of a bracket provided with a fixed ledge and adapted to be secured to the outer side of a wall or jamb, a loop, forming with said ledge a clamp and passing 55 through said bracket and having an arm adapted to pass through said wall or jamb, and locking means, adapted to be arranged at the inner side of said wall or jamb and to lock said arm, to prevent the opening of said 60 clamp, said bracket being also provided with a shelf, arranged above said ledge, to cover a jar held in said clamp and to prevent the removal of the stopper of said jar.

5. The combination of the bracket having 65 a ledge, a loop, passing through said bracket and having an arm adapted to pass through a wall or jamb and provided with a latch, adapted to engage a stationary projection from the inner face of said wall or jamb and 70 to prevent the opening of said loop.

6. The combination of the bracket adapted to be secured to the outer face of a wall or jamb, a loop, passing through said bracket and having an arm adapted to reach through 75 said wall or jamb, a latch adjustably secured on said arm at the inside of said wall or jamb and a stop, adapted to be supported by the inner face of said wall or jamb and to be engaged by said latch, to prevent said loop from 80 being drawn away from said bracket.

7. The combination of the bracket, adapted to be secured to the outer face of a wall or jamb, a loop, passing through said bracket and having an arm adapted to reach through 85 said wall or jamb, and having an external screw-threaded free end portion, a nut, engaging said screw-thread, a latch, pivoted to said nut, and a stop adapted to be supported by the inner face of said wall or jamb and to 90 be engaged by said latch, to prevent the drawing of said loop away from said bracket.

In testimony whereof I have affixed my signature in presence of two witnesses.

FRANK S. TWOMBLY.
